UNITED STATES PATENT OFFICE.

RANDOLPH CROMPTON, OF CHATHAM, AND WILLIAM E. WOODMAN, OF WORCESTER,
MASSACHUSETTS.

MAGAZINE FOR WEFT-REPLENISHING LOOMS.

1,270,707.

Specification of Letters Patent. Patented June 25, 1918.

Application filed September 25, 1915. Serial No. 52,709.

To all whom it may concern:

Be it known that we, RANDOLPH CROMPTON and WILLIAM E. WOODMAN, both citizens of the United States, and residents, respectively, of Chatham and Worcester, in the counties, respectively, of Barnstable and Worcester and State of Massachusetts, have invented an Improvement in Magazines for Weft-Replenishing Looms, of which the following description, in connection with the accompanying drawings, is a specification, like characters on the drawings representing like parts.

This invention relates to magazines for weft replenishing looms, and particularly to improvements in subsidiary magazines for such looms.

In order that the principle of the invention may be readily understood, we have disclosed a single embodiment thereof in the accompanying drawings, wherein—

Fig. 1 is a view, partly in side elevation and partly in vertical section, of a subsidiary magazine embodying our invention;

Fig. 2 is a view, partially in end elevation and partially in horizontal section, of a master magazine for weft replenishing looms having a plurality of subsidiary magazines constructed in accordance with our invention;

Fig. 3 is a view, partially in end elevation and partially in horizontal section, representing other portions of the master magazine;

Fig. 4 is a detail in vertical section of a portion of one of the subsidiary magazines;

Fig. 5 is a vertical section upon the line 5—5 of Fig. 1 and looking toward the left in said figure;

Fig. 6 is a detail in side elevation of the tip of one of the bobbins and the support therefor;

Fig. 7 is a vertical section on the line 7—7 of Fig. 1; and

Fig. 8 is an end elevation of the thread-receiving spindle of one of the subsidiary magazines.

This invention in certain aspects thereof is an improvement upon the construction disclosed in the patent to Randolph Crompton, No. 1,142,938, dated June 15, 1915.

Referring more particularly to the drawings, we have in Figs. 2 and 3 represented

a substantially circular disk-like member 1, which is preferably similar to the corresponding part in said patent. The said member 1 is preferably mounted at the right hand end of the loom and upon the framing 2 thereof. The said member 1 is fixedly mounted upon the shaft 3 in any suitable manner and preferably as shown in said patent. The shaft is preferably provided with an operating cam indicated at 4 in dotted lines and with co-acting members or parts for the operation of the subsidiary magazine. Preferably mounted as disclosed in said patent is a star wheel 5 and a hub 6 provided with a series of radial sockets wherein are mounted any desired number of arms or spokes 7, herein shown as twelve in number, and corresponding in function to the arms or spokes of said patent. Upon each of said arms or spokes is mounted for sliding movement what we herein term a subsidiary magazine comprising or including a casting 8. Said subsidiary magazines, four of which are herein shown, are normally supported in their inner positions by means of a spring 9 herein shown as a coil spring circular in form and the ends of which may be hooked together, so as to engage with suitable studs or pins 10 upon said castings 8. As set forth fully in said patent, the subsidiary magazines are periodically moved radially downward into co- operate relation with the shuttle in the shuttle box.

Each of said subsidiary magazine castings is provided with a member 11 constituting a support for the bases of a series of bobbins or other suitable weft carriers indicated at 12, and herein shown as four in number. These weft carriers correspond in color or other distinguishing characteristics with the filling in the several shuttles. The member 11 is herein represented as having the form of a cross, and the tip ends of the bobbins 12 are suitably supported in a correspondingly shaped cross member 13 shown most clearly in Fig. 5, thereby to support the bobbins with suitable spring pressure and shaped as indicated so as frictionally to support the tips of the bobbins.

Extending through each casting 8 is a shaft 14 having a suitable bearing therein and herein shown as threaded at 15 to re-

ceive nuts 16, 17 whereby the tip holding member 13 is held in position. Fast upon said shaft 14 is a pinion 18 which as shown most clearly in Fig. 4, is provided with a 5 shallow socket 19 adapted to receive the curved or rounded end of a pin or plunger 20 which is normally pressed toward said pinion by a coiled spring 21 seated in a socket 22 in the casting 8.

10 Each of said gears 18 is of the general construction disclosed in said patent and they coöperate with a rack 23 formed or provided upon a swinging segment 24 similar to that shown in said patent and preferable 15 similarly operated.

In the operation of the replenishing mechanism, it is important that in all the subsidiary magazines the colors be correspondingly positioned prior to the engagement of 20 each subsidiary magazine with the oscillatory rack 23. When the subsidiary magazines are replenished, it frequently occurs that the colors in the several magazines do not occupy corresponding positions and that 25 the gears thereof are so turned that when replenishment occurs, the several weft carriers are not properly positioned. In order to permit the loom attendant manually to position each subsidiary magazine prior to 30 its engagement with the rack 23, we have provided the pin or plunger 20 whereby the attendant may grasp a portion of each subsidiary magazine and turn it until the said pin or plunger 20 enters the socket 19. The 35 loom attendant, hearing the resulting click, or from the feel of the parts, will know that the bobbins of such subsidiary magazine are properly positioned. In this manner each of the subsidiary magazines is properly positioned, and when each in turn engages the 40 oscillatory rack 23, the latter will rotate the subsidiary magazine to the proper extent, as set forth in my patent, thus disengaging and, if the movement of the parts requires 45 it, again engaging the plunger 20 with the socket 19. The construction of parts is such that plunger 20 may be disengaged and again engaged a number of times by the rack 23 before such subsidiary magazine is 50 finally moved out of operative position with said rack.

We have herein represented the shaft 14 as having an enlarged outer end 25 herein shown as of conical form at 26 and terminating in a head 27 preferably cross slotted as indicated at 28, 29. The said cross slits 28, 29 are preferably continued along the conical surface of the shaft, one of the said continuations being indicated at 30 in Fig. 55

60 1. In that form of our invention herein shown, four slits 30 are provided, spaced apart ninety degrees circumferentially of the shaft portion 26.

The yarns or threads are drawn from the 65 several bobbins, two of them being indicated

at 31 in Fig. 1. The said threads are passed to the head 27 and enter the appropriate slit 28 or 29 therein and after passing therethrough emerge therefrom and are wrapped spirally about the conical portions 26 of the 70 shaft 14, as indicated at 32 in Fig. 1, thus holding the thread ends while the bobbins are supported in the subsidiary magazine. In order to permit the ready removal of the wrapped portions of the threads, the slit 75 continuations 30 are provided along which a knife may be drawn, thereby severing the threads.

In order to prevent breaking of the threads that extend from the bobbins across 80 the ends of the tip supporting member 13, we preferably provide upon each arm of said member 13 a wire 33, herein shown as of one piece and bent upon itself as shown so as to embrace or be wrapped about the 85 arms of the member 13 and to provide a guide portion 34 along which the thread may extend and which offers no sharp edge to the thread and therefore will not break the same. While instead of the wire 33 any 90 other suitable means may be provided, the construction shown is simple and effectively serves the intended purpose.

The operation of the subsidiary magazines is in general that disclosed in the said 95 patent, and it is unnecessary to set forth the same in detail.

The employment of the pin or plunger 20 for each subsidiary magazine permits in 100 a simple manner the proper positioning manually of the several bobbins of each magazine prior to the engagement of each pinion 18 with the rack 23.

Having thus described one illustrative embodiment of our invention, we desire it 105 to be understood that although specific terms are employed, they are used in a generic and descriptive sense and not for purposes of limitation, the scope of the invention being set forth in the following 110 claims.

Claims:

1. A weft replenishing loom provided with a magazine having a subsidiary magazine adapted to hold a plurality of bobbins, and means to check said second mentioned magazine when turned manually to a given position.

2. A weft replenishing loom provided with a magazine having a subsidiary magazine adapted to hold a plurality of bobbins mounted for rotation thereabout, and plunger and socket means to hold said second mentioned magazine when rotated into the desired position when refilling said magazine.

3. A weft replenishing loom provided with a magazine having a subsidiary magazine adapted to hold a plurality of bobbins mounted for rotation thereabout, a gear co-

- operating with said master magazine and provided with a socket and a coöperating plunger carried by said second mentioned magazine whereby the magazine may be held 5 in desired position.
4. A weft replenishing loom provided with a magazine having a subsidiary magazine adapted to hold a plurality of bobbins mounted for rotation thereabout, said subsidiary magazine having a shaft provided with a pinion 18 coöperating with said master magazine and having a socket upon its face and a spring pressed plunger 20 carried by said second mentioned magazine and co-10 operating therewith.
5. A magazine for a weft replenishing loom having a bobbin tip holder having a wire extension wrapped thereabout and shaped to provide a guide portion 34 for the 15 thread.
6. A magazine for a weft replenishing loom provided with a plurality of bobbins, and a supporting shaft with respect to which said bobbins are concentrically ar-20 ranged, said shaft having a slotted terminal to receive the thread ends extending from the bobbins.
7. A magazine for a weft replenishing loom having a plurality of bobbins, and a supporting shaft with respect to which said bobbins are concentrically arranged, said shaft having a cross slotted end and an adjacent portion slotted in continuation of said 25 cross slits.
8. A magazine for a weft replenishing loom having a plurality of subsidiary magazines mounted for radial movement and a single spring in circular form co-acting with each of said magazines to maintain them in 30 their inner positions.
9. A weft replenishing loom provided with a magazine adapted to hold a plurality of bobbins mounted for rotation, and a gear coöperating with said magazine, one of said 35 parts being provided with a socket and the other being provided with a plunger, whereby said magazine may be held in desired position.
10. A weft replenishing loom provided 40 with a magazine adapted to hold a plurality of bobbins mounted for rotation, and a gear coöperating with said magazine, said gear being provided with a socket and said magazine being provided with a plunger to enter
- said socket, whereby said magazine may be 55 held in desired position.
11. A weft replenishing loom provided with a magazine adapted to hold a plurality of bobbins, and means to check said magazine when turned manually to a given position, whereby any desired bobbin of a plurality of bobbins may be presented to function in the replenishing operation. 60
12. A weft replenishing loom having a master magazine provided with one or more subsidiary magazines, each subsidiary magazine having a plurality of bobbins, and a supporting shaft with respect to which said bobbins are concentrically arranged, said shaft having a slotted terminal to receive the 65 thread ends extending from said bobbins.
13. A weft replenishing loom having a master magazine provided with one or more subsidiary magazines, each subsidiary magazine having a plurality of bobbins, and a supporting shaft with respect to which said bobbins are concentrically arranged, said shaft having a cross slotted end and an adjacent portion slotted in continuation of said 70 cross slits. 75
14. A weft replenishing loom provided with a magazine having a subsidiary magazine adapted to hold a plurality of bobbins, and means to check said second mentioned magazine when moved manually to a given 80 position.
15. A weft replenishing loom having a main magazine and a plurality of subsidiary magazines, each of the latter having a gear, and a co-acting bobbin supporter, one of 85 said two parts, namely, the gear and the bobbin supporter, being provided with a socket, and the other thereof being provided with a plunger. 90
16. A weft replenishing loom provided with a main magazine and a plurality of gears 18 mounted thereon and each having a co-acting bobbin support, each bobbin support and its co-acting gear being provided with co-acting socket and plunger means. 95

In testimony whereof, we have signed our names to this specification in the presence of two subscribing witnesses.
